UNITED STATES PATENT OFFICE

2,422,708

AGITATING MIXING DEVICE

Charles F. Warren, Milwaukee, Wis.

Application April 26, 1944, Serial No. 532,748

8 Claims. (Cl. 259—113)

1

This invention relates to devices for mixing materials particularly by means of a vibrating stirrer or dasher which agitates the material to facilitate its intermixture or to maintain it in that condition.

One object of the invention is to provide a container for the material to be mixed or agitated, together with a vibratory member or dasher within the container and means outside the container having operative connection with the vibrator or dasher therein which does not involve any sliding movement of such connection through the wall of the container.

Another object of the invention is to provide a container having one of its walls or a portion thereof made of flexible material and provided with a dasher or agitating member mounted within the container in engagement with such flexible wall together with vibrating means outside the container and also engaging said wall for transmitting vibration to the dasher.

It is also an object of the invention to provide a container having one wall or a portion thereof constructed of flexible material and provided with a dasher mounted in the chamber and with yielding means holding the dasher in contact with such flexible wall together with vibrating means mounted outside the chamber in contact with the flexible wall for transmitting vibration to the dasher and means for adjusting the tension of the yielding means so that the dasher and its associated parts may be given a normal frequency of vibration in excess of the maximum frequency delivered to it by the vibrating means.

It is also an object of the invention to provide a container having an opening in one wall with a flexible diaphragm sealing such opening and with a dasher or vibrating member mounted within the chamber and held yieldingly in engagement with such diaphragm together with a rotary cam or eccentric device outside the chamber and a plunger interposed between such cam or eccentric and the diaphragm for causing rapid vibration of the diaphragm and dasher in response to rotation of the cam device.

Other objects and advantages of the invention will appear from the following description taken in connection with the drawings in which:

Fig. 1 is a top plan view of a container provided with agitating means embodying this invention.

Fig. 2 is a vertical sectional view taken substantially as indicated at line 2—2 on Fig. 1.

Fig. 3 is a transverse vertical section taken as indicated at line 3—3 on Fig. 2.

2

Fig. 4 is a vertical sectional view taken at the same plane as Fig. 2 but showing a modified form showing a plurality of dashers.

Fig. 5 is a vertical sectional view taken similarly to Fig. 2 but showing another modification in which the dasher controlling springs are in tension instead of in compression.

Fig. 6 is also a vertical sectional view taken diametrically with respect to the container and showing a further modification in which the diaphragm and dasher are anchored to an eccentric-driven pitman.

While the invention is susceptible of various modifications and alternative constructions, the embodiments shown in the drawings and described hereinafter are by way of preferred illustration only, and it is not intended that the invention be limited thereto or thereby, but it is the intention to cover all modifications and alternative constructions falling within the scope of the invention as defined by the claims.

In mixing certain materials including various liquids and some gases or combinations of liquids and gases, or mixtures of finely divided solids which are held in suspension in liquids, it is frequently desirable to churn or agitate the mixture by means of a rapidly vibrating paddle or dasher; and in the handling of such materials it is desirable that a container be provided therefor which does not require an opening through which an actuating member extends for vibrating or oscillating the dasher within the container.

In order to avoid such a construction involving the provision of an opening in the wall of the container the present invention provides one such wall with a flexible portion which may be in the nature of a flexible diaphragm secured in sealing engagement over an opening in the more rigid portion of the wall. External force applied to such flexible diaphragm is then employed to vibrate the dasher or agitating member mounted within the chamber in engagement with the inner face of the diaphragm.

In the structure shown in Figs. 1, 2 and 3, the container consists of a cylindrical vessel 1 having a flat bottom wall 2 with an opening 3 cut in the central portion of such wall and with a flexible diaphragm 4 secured over this opening. The diaphragm is shown as consisting of two layers but it may be understood that it may be formed of a single piece of material if preferred or of a larger number of laminae whenever that seems desirable. As shown, the diaphragm 4 is clamped in sealing engagement with the bottom wall 2 by means of bolts 5 and 6 which extend

through a clamping ring 7 engaging the inner face of the bottom wall 2, and which also engage the annular flange 8 of a housing 9 of a mechanical stroke-imparting device by which the diaphragm 4 is vibrated.

In the form shown, the stroke-imparting device includes a rotary drive shaft 10, keyed to a rotary member 11, which is journaled in the housing 9 by means of ball bearings 12 and 13 and which includes an eccentric portion 14 on which a ring 15 is journaled on ball bearings 16. The ring 15 engages a plunger 17 slidable in a guide-way 18 which is formed in the housing 9 and at its upper end the plunger 17 contacts the diaphragm 4.

Within the container 1 there is mounted an agitating member or dasher 20 which is shown in the form of a disk somewhat smaller than the internal diameter of the container 1 and which includes a depressed central portion or hub 21 bearing upon the upper side of the diaphragm 4. The dasher 20 is positioned and guided by rods 22 which, as shown, are the upwardly extending portions of the clamping bolts 6, three of which are thus constructed as guide rods passing through bushings 23 in the dasher disk 20 and carrying coiled springs 24 which react between the bushings 23 and stop nuts 25 on the threaded upper ends of the rods 22.

Thus it will be clear that as the shaft 10 is rotated the eccentric 14 turning within the ring 15 will cause the latter to rise and fall so as to transmit reciprocatory movement to the plunger 17, this movement being transferred through the diaphragm 4 to the hub 21 of the dasher disk 20 causing the latter to be vibrated vertically in response to the rotation of the shaft 10. The nuts 25 will be adjusted so as to tension the springs 24 sufficiently to maintain the hub portion 21 of the dasher in contact with the diaphragm 4 and bearing firmly against the plunger 17 to insure that the dasher 20 shall faithfully follow the reciprocatory movement of the plunger induced by rotation of the eccentric 14. In other words, the resilient mounting of the dasher consisting in this case of the springs 24, is so tensioned that the assembly under control of the springs will have a normal frequency of vibration somewhat higher than the maximum frequency which will be imparted to it by the eccentric 14 and plunger 17, thus insuring that the dasher 20 may be actuated at any desired frequency up to the maximum depending upon the material under treatment and the condition to be produced therein by means of the agitating treatment. For most purposes the dasher disk 20 will have a series of perforations 26 disposed in any convenient arrangement within its area.

In the drawings the container 1 is shown as open at the top but it will be understood, of course, that a cover may be provided if desired and that means for sealing the cover in gas tight or liquid tight relation may also be provided. Furthermore, in some cases, it may be more convenient to arrange the mounting of the dasher 20 on a removable cover or in some other wall of the container, all of which is within the scope of the present invention.

Fig. 4 shows a slight modification of the arrangement shown in Figs. 1-3, in that several dashers 20, 20a and 20b are mounted in superimposed relation within the container 1 with the hub portion 21b of the dasher 20b resting upon the central portion of the dasher 20a, and with the hub portion 21a of the dasher 20a resting

upon the central portion of the dasher 20. The reciprocation of the plunger 17 thus serves to actuate all three dashers simultaneously and their movement is guided by elongated rods 22a which are similar to the rods 22 except for their linear dimension. Control springs 24 are carried by the rods 22a with stop nuts 25 arranged for adjusting the tension of the springs.

Fig. 5 shows another modification in which the rotary drive mechanism is similar to that shown in Fig. 2 and includes the shaft 10, eccentric 14 and plunger 17. The diaphragm 30 is shown as of a single thickness and is clamped against the bottom wall 2 of the container 1 in substantially the same manner as in Fig. 2, by means of clamp bolts 5 and 5a. A clamp ring 7 is disposed inside the container and may be seated upon a sealing gasket 7a if desired. The bolts 5a are slightly longer than the bolts 5 and serve to anchor the lower ends of conical coiled springs 31 which control the dasher 32 of this structure. The upper conical portions of the springs 31 engage in downwardly tapering openings 33 in the dasher and the springs thus serve to draw the dasher yielding toward the upper face of the diaphragm 30. Instead of an integral hub, the dasher is shown as provided with a central screw 34 having a head 35 at its lower end fitted into a cup 36 of rubber or like resilient material which is seated directly upon the diaphragm 30. The central bore in the dasher disk 32 is threaded at 37 for engagement with the threads of the screw 34, and the upper end of the screw is slotted at 38 to receive a screw driver or similar tool by which it may be adjusted axially in the dasher disk for varying the distance of the disk from the bottom of the container and at the same time varying the tension of the springs 31. A lock nut 39 on the screw 34 engages the top of the disk 32 to secure the parts in adjusted relation.

Fig. 6 shows a further modification in which a rotary drive shaft 40 is journaled in a housing 41 by means of ball bearings 42 and 43. The shaft 40 includes an eccentric portion 44 which engages in an eccentric strap 45 of a pitman 46 so that rotation of the shaft 40 oscillates the pitman 46 vertically within the housing 41. The bottom wall 2 of the container 1 has an opening 3 and a flexible diaphragm 50 is secured over this opening with its peripheral portion clamped to the bottom wall 2 in sealing engagement therewith. The clamping bolts 47 extend through a flange 48 of the housing 41 and through a clamping ring 49 disposed within the container 1 and bearing upon a sealing gasket 51 which contacts the upper face of the bottom wall 2. The pitman 46 includes an extension 52 which passes through a central opening in the diaphragm 50 but this opening is sealed when the diaphragm is clamped between a flange 53 of the pitman 46 and a spacer sleeve 54 carried on the extension 52. The upper end of the extension is threaded at 55 and an agitator plate or disk 56 is secured between the upper end of the sleeve 54 and a clamping nut 57 engaging the threads at 55. The nut 57 thus serves the dual purpose of securing the agitator disk 56 in position and forcing the sleeve 54 into clamping engagement with the central portion of the diaphragm 50. With the pitman 46 connected directly to the eccentric 44, it will be evident that its motion will not be strictly of a reciprocating nature but the flexible diaphragm 50 will accommodate itself to the obliquity of the pitman 46 as it is oscillated in response to rotation of the shaft 40 and its eccentric 44. The

corresponding movement of the dasher plate 56 will involve a slight tilting of the plate out of the horizontal plane but the vibratory action of the agitator will be just as effective for most purposes as the movement produced in the other forms of the device already described.

It will be evident that the principle of this invention will have wide application. It is adapted not only to industrial and manufacturing processes, but in the domestic field it may be employed in washing machines, egg beaters, drink mixers, dish washers, and various other mechanisms in which it is required to provide a container with a movable agitating member therein.

I claim as my invention:

1. In an agitating device, a container having an opening in one wall, a flexible diaphragm covering said opening, a stroke-imparting device operable against the outer side of said diaphragm, a dasher in the container, resilient means holding said dasher firmly against the inner side of said diaphragm for vibration in response to said stroke-imparting device, and tensioning means for said resilient means adjustable to give the resiliently held dasher a normal frequency of vibration higher than the maximum frequency of the strokes imparted thereto by the stroke-imparting device.

2. In an agitating device, a container having an opening in one wall, a flexible diaphragm covering said opening, a rotary cam device and a plunger operable thereby against the outer side of said diaphragm, a dasher in the container, resilient means holding said dasher firmly against the inner side of said diaphragm for vibration in response to said eccentric, and tensioning means for said resilient means adjustable to give the resiliently held dasher a normal frequency of vibration higher than the maximum frequency of the vibrations imparted thereto by rotation of the eccentric.

3. An agitator comprising, in combination, a container having an opening in one wall, a flexible diaphragm sealed over said opening, guide means extending in the container, a dasher slidably mounted on said guide means with a part extending from said dasher into engagement with the diaphragm, spring means carried by said guide means, and holding said part firmly against the diaphragm, and a rotary cam device, operable against the outer side of the diaphragm.

4. An agitator comprising, in combination, a container having an opening in one wall, a flexible diaphragm covering said opening, guide rods extending rigidly in the container from said wall, a dasher slidably mounted on said guide rods with a part extending from said dasher into contact with the inner side of the diaphragm, springs on said rods bearing resiliently against the dasher, adjustable stop nuts for said springs on the rods, and a rotary cam device operable against the outer side of the diaphragm.

5. An agitator comprising, in combination, a container having an opening in one wall, a flexible diaphragm covering said opening, guide rods extending rigidly in the container from said wall, a plurality of dashers mounted slidably on said guide rods with spacing means separating said

dashers from each other and from said diaphragm, springs on said rods bearing against one of said dashers and rendering said spacing means effective to transmit motion from the diaphragm to said dashers, and a rotary cam device operable against the outer side of the diaphragm.

6. In an agitating device, a rotary shaft, a bearing support in which said shaft is journaled, a mounting flange rigidly connected to said bearing support, a container having an opening in one wall, a flexible diaphragm covering the opening and interposed between the mounting flange of said bearing support and the marginal portion of said wall around the opening, clamping bolts securing said flange to said wall, a stroke-imparting device operable by said shaft against the outer side of said diaphragm, a dasher in the container having a connection extending into constant engagement with said flexible wall, said 10 clamping bolts extending into the container and through the dasher, serving as guides upon which said dasher is slidably mounted, springs coiled around said guides and abutments on the guides, said springs reacting between said abutments and the dasher to maintain the constant engagement 15 of said connection with the diaphragm.

7. In an agitating device, a container having an opening in one wall, a flexible diaphragm sealed over said opening, a rotary cam device and 20 a plunger operable thereby against the outer side of said diaphragm, a dasher in the container, a threaded stem extending from the dasher into engagement with the inner side of the diaphragm and resilient means reacting between the dasher 25 and said wall of the container to maintain said stem in engagement with the diaphragm for causing the dasher to be vibrated in response to the operation of the cam device, said stem being adjustable to vary the pressure maintained by 30 said resilient means.

8. In an agitating device, a container having a flexible wall, a stroke-imparting device operable against the outer side of said wall, a dasher in the container, resilient supporting means holding 45 said dasher firmly against the inner side of said wall for vibration in response to said stroke-imparting device, and tensioning means for said resilient support adjustable to give the dasher a normal frequency of vibration higher than the maximum frequency of the strokes imparted thereto by the stroke-imparting device.
